UNITED STATES PATENT OFFICE

FREDERICK W. ANDREW, OF BROOKLYN, NEW YORK.

LOCK.

Application filed December 13, 1920. Serial No. 430,140.

To all whom it may concern:

Be it known that I, FREDERICK W. ANDREW, a citizen of the United States, and a resident of the city of New York, borough 5 of Brooklyn, county of Kings, and State of New York, have invented certain new and useful Improvements in Locks, of which the following is a specification.

My invention relates to locks, and its particular object is to provide a burglar-proof 10 door lock of exceedingly simple construction and yet possessing great strength, so that it is practically impossible to open the lock in an unauthorized way.

I am aware, of course, that so-called burglar-proof locks have heretofore been designed and used, but the lock of my invention embodies certain features of novelty which impart to it decided advantages over 15 prior structures, as will appear from a detailed description of the lock shown in the accompanying drawings.

One of the features of my new lock is a locking member in the form of a disk which 20 is preferably flanged and made of hardened steel. When this disk is in locking position, the projecting portion thereof interlocks with a shoulder on the keeper secured to the door casing. When the disk is in normal or 25 unlocking position, it is housed entirely within the casing of the lock.

The locking disk is operated from one side of the door by a knob or like member and from the other side of the door by a 30 key-controlled lock of any approved construction (such as any type of cylinder). Provision is made whereby the locking disk is positively locked in actuated position, so that it cannot be operated by merely turning 35 the knob. It is first necessary to manipulate the knob in a prescribed manner to unlock the disk for rotation. This will be specifically referred to later on.

In the accompanying drawings—

Fig. 1 shows a lock embodying my invention as applied to a door;

Fig. 2 is a vertical cross-section approximately on line 2—2 of Fig. 1;

Fig. 3 is a view taken on the broken line 50 3—3 of Fig. 1, looking in the direction of the arrows.

Fig. 4 is a sectional view approximately on line 4—4 of Fig. 2, showing the locking disk in normal position within the casing;

Fig. 5 is a view similar to Fig. 4, showing the locking disk in locking position;

Fig. 6 is an edge view of the lock, a portion being broken away to show certain parts within the casing;

Fig. 7 is a perspective view of my new 60 locking disk; and

Fig. 8 is a detached view showing the connection between the locking disk and the key-controlled lock by means of which the disk is operated from the outside of the 65 door.

For the sake of explaining my invention, I am assuming that my new lock is applied to the entrance door of a dwelling or an apartment, although it may be used on inside 70 doors and elsewhere. In the drawings the door is represented by A and the casing or door-jamb by B. The side of the door shown in Fig. 1 is supposed to be the inside. The outer casing C of the lock is, roughly speaking, circular in shape, except that it has a straight edge 1 adapted to lie substantially flush with the edge of the door when the lock is in position. The casing C may conveniently be formed of a back-plate 2 and a 75 box-like section 3, these two parts fitting together to form a closed casing. In practice, the parts 1 and 3 of the casing are preferably cast of a suitable metal, such as bronze, or the like. The casing is secured to the door by 80 screws 4 which pass through aligned openings in the parts 1 and 3.

Within the circular chamber of the casing C is mounted the locking disk 5. This disk is of heavy construction and is preferably 90 made of hardened steel, or some such metal. As seen from Figs. 4 and 5, the disk practically fills the inside of the casing. This permits a large heavy locking disk to be housed within a casing not much larger 95 than the disk itself, thus producing a lock of compact proportions, and yet one which contains a locking member of great strength. The disk 5 is preferably formed with a lateral flange 6, which increases its strength. 100

The peripheral flange 6 projects axially from one side only of the body of the disk, so that the disk may be formed from a cut-punching. A segment of the disk is cut away to provide an edge 7 (see Fig. 7), 105 which lies substantially flush with the edge of the casing when the disk is in normal or unlocking position, as best shown in Fig. 4. The edge 1 of the casing is provided with a flange-shaped slot or opening 8 (see 110 Fig. 6) of substantially the same outline as the flange-shaped edge 7 of the disk 5.

The locking disk 5 is adapted to be turned from the inside of the door by any suitable hand-operated member, such as a knob 9, which is secured to the outer end of the 5 shaft 10. I may here state, that when I use the term "knob" in the claims, I do so for conveniently describing any suitable part projecting from the casing to be operated by hand. On the inner end of the 10 shaft 10 is rigidly mounted a connecting piece 11. The disk 5 is provided with an opening 12 of a shape to receive the connecting piece 11. To permit a slidable movement of the connecting piece 11 without 15 breaking its operative connection with the locking disk 5, the connecting piece is provided with a pair of axial flanges 13. Suitable spring means, such as a spring 14 surrounding the shaft 10, normally holds the 20 connecting piece 11 toward the disk, as shown in Fig. 2. The coil-spring 14 may be conveniently located in the recess 15 of the casing C, so that one end of the spring bears 25 against the casing and the other end against the connecting piece 11, as best shown in Figs. 2 and 3. When the knob 9 is pulled out against the tension of the spring 14, the connecting piece 11 is moved away from the locking disk 5, but not sufficiently to break 30 the operative connection between the connecting piece and the disk, as may be seen from Fig. 6.

One of the flanges 13 of the connecting piece 11 has a rearwardly extending lug 16 arranged to be engaged by a lug 17 on a small circular plate 18 arranged at the inner end of a suitable key-actuated lock fixed in the door. This lock, which I have indicated as a whole by Y, may be of any 35 approved type, such as any type of cylinder, and since the lock Y does not in and of itself form part of my present invention, I need not describe its details of construction. It is sufficient to say, that the member 18 40 is a key-actuated element adapted to engage the connecting piece 11 and thereby operate the locking disk 5. It is clear from Fig. 8, that when the lug 17 of the element 18 engages the lug 16 of the connecting piece 11, the disk 5 is rotated into one position or the other. Thus, by operating the lock Y by a 45 key K, a person can either lock or unlock the disk 5 from the outside of the door.

When the disk 5 is in locking position, as 55 shown in Fig. 5, a portion thereof projects beyond the casing C into a suitable keeper 19, secured to the door-jamb B by screws 20 and 21, or otherwise. I prefer to provide the keeper 19 with a shoulder or boss 22, 60 with which the flange 6 of the locking disk interlocks when the disk is in locking position. In other words, the flange 7 hooks over the shoulder 22 of the keeper. It will be seen from this, that the locking disk 5 65 forms a strong locking connection. An at-

tempt to cut or saw through this disk by the insertion of an instrument into the joint between the lock and the keeper, is practically impossible, for the disk 5, besides being made of hardened steel, has the added 70 strength of the flange 6. The interlocking engagement between the disk 5 and the keeper 19 resists any attempt of a person to force the lock by pressure against the door. The disk 5, it will be observed, is a 75 passive disk. That is to say, it is not spring-actuated and remains in whatever position it is turned by hand until moved out of that position by the knob or key. Furthermore, the knob 9 and key-actuated member 18 are in axial alignment with the disk 5 and directly connected thereto without any intermediate driving connections such as gears and the like. The direct operative connections for the disk and the absence of all 80 springs (with the exception of the small spring 14) render the lock exceedingly simple and compact.

Any suitable means may be provided for limiting the rotary movements of the locking disk 5. In the drawings I have shown the disk provided with an arcuate slot 23, in which engages a stop 24 carried by the casing C. For convenience of manufacture, the stop 24 may be a screw or bolt which 95 fastens the back-plate 2 to the main section 3 of the casing.

When the disk 5 has been actuated by means of the element 18 of the lock Y, as above explained, it is impossible to operate 100 the disk by merely turning the knob 9, because the lug 17 of the element 18 is in the path of movement of the lug 16 on the connecting piece 11, whereby the disk 5 and the knob 9 are normally locked against rotary 105 movement. In order, therefore, to turn the disk 5 by means of the knob 9, it is first necessary to pull the knob out, so as to move the lug 16 out of the way of the lug 17, as shown in Fig. 6. Then the knob is free to 110 be turned and the locking disk 5 may be moved into the desired position. As soon as the knob 9 is released, the spring 10 pushes the connecting piece 11 inwardly, and thus throws the lug 16 again into locking 115 relation to the lug 17. In other words, the disk 5 is always locked in one position or the other by the lugs 16 and 17, so far as the knob 9 is concerned, and it is necessary, in the preferred construction shown, to 120 pull the knob out before it can be turned. This prevents an unauthorized person from unlocking the disk 5 from the outside by an attempt to turn it otherwise than through the element 18.

I may also provide means for locking the disk 5 in locked position to prevent unlocking thereof by a person having a key to the lock Y. This locking of the disk 5 may be done in several ways, and for the sake of il- 130

lustration I have simply shown a set-screw 25, which in normal position does not engage the disk 5, as shown in Fig. 2. When the disk is in locking position and it is desired to lock the same (as for the night), the set-screw 25 is given a few turns until the inner end thereof engages in the slot 23 of the disk, as shown in Fig. 5. This locks the disk 5 against movement into unlocking position 10 until the set-screw 25 is withdrawn from the slot 23.

To prevent the lock Y from being turned bodily in the door, I interpose a square plate 26, which fits into a correspondingly shaped recess 27 in the back of plate 2 of the lock casing. The plate 26, of course, need not be square, as any non-circular shape would be sufficient to prevent turning thereof. The element 18 is connected to a series of small circular plates 28, of which three are shown in Fig. 2. The plates or disks 28 are arranged on one side of the plate 26 and the disk 18 on the other side. A smaller disk 29 is arranged between the disk 18 and the disks 28 and operates in an opening of the plate 26, thereby forming a bearing for the disk 18. The disks 28 are provided with a slot into which extends a flat piece 20 projecting from the lock Y. The extension 30, which is part of the lock Y as bought in the store, may be cut or broken off to the desired length, depending upon the thickness of the door in which the lock is inserted.

I have already referred to the interlocking engagement between the flanged disk 5 and the shoulder 22 of the keeper 19. An additional advantage of this construction resides in the fact that the locking disk and the keeper are interlocked against lateral separation. This renders my new lock applicable to sliding doors by fastening the casing C to one door and the keeper 19 to the other door (in the case of double sliding doors), or to the door casing (in the case of a single sliding door).

It will be seen from the foregoing that I have produced a very simple and efficient lock, which consists of but few parts, may be manufactured at a comparatively low cost, and which possesses unusual strength and durability. While I have shown and described a specific construction, I would have it understood that I do not intend to be limited to the details herein set forth, for it is obvious that changes and modifications may be made without departing from the scope of the invention as defined in the appended claims.

I claim as my invention:

1. In a lock, a casing having an edge provided with an opening, a locking disk rotatably supported within said casing and having a segment cut away to form an edge adapted to lie substantially flush with said edge of the casing when the disk is in nor-

mal or unlocking position, a portion of said disk projecting through said opening beyond said edge of the casing when the disk is in locking position, a knob projecting from one side of the casing in axial alignment with said disk and operatively connected thereto, key-controlled mechanism also in axial alignment with said disk for operating said disk from the other side of the casing, and means operable from the first-mentioned side of the casing for engaging said disk and thereby locking the same in locking position to prevent unlocking thereof by said key-controlled mechanism.

2. In a lock, a casing having an edge provided with an opening, a locking disk rotatably supported within said casing and having a segment cut away to form an edge adapted to lie substantially flush with said edge of the casing when the disk is in normal or unlocking position, a portion of said disk projecting through said opening beyond said edge of the casing when the disk is in locking position, a knob projecting from one side of the casing for operating said disk, a key-controlled element arranged to be operated from the other side of the casing, co-operating parts connected with said disk and said element for turning the disk by means of said element, said co-operating parts normally locking the disk against movement by said knob, and means for separating said co-operating parts to permit rotation of said locking disk by the knob.

3. In a lock, a casing having an edge provided with an opening, a locking disk rotatably supported within said casing and having a segment cut away to form an edge adapted to lie substantially flush with said edge of the casing when the disk is in normal or unlocking position, a portion of said disk projecting through said opening beyond said edge of the casing when the disk is in locking position, a knob projecting from one side of the casing in axial alignment with said disk for turning the same, a key-controlled element arranged in axial alignment with said disk and adapted to be operated from the other side of the casing, a member at the center of said disk for operatively connecting said knob and said element with said disk, said member normally locking said disk against rotation by said knob, and means whereby an axial movement of said knob disconnects said member from said element and permits operation of said disk by turning the knob.

4. In a lock, a casing having an edge provided with an opening, a locking disk rotatably supported within said casing and having a segment cut away to form an edge adapted to lie substantially flush with said edge of the casing when the disk is in nor-

- normal or unlocking position, a portion of said disk projecting through said opening beyond said edge of the casing when the disk is in locking position, a knob projecting from one side of the casing and having a shaft operatively connected at its inner end to said disk for turning the latter into locking and unlocking positions, said shaft being axially movable without breaking its operative connections with said disk, a projection connected with said shaft, a stop arranged in the path of said projection to lock said disk against operation by the knob, said projection being movable out of the way of said stop by an axial movement of said shaft, 75 whereupon the knob may be turned to rotate said disk, and spring means for normally holding said projection in the path of said stop.
- 10 to said disk without breaking its operative connection with the disk, a lug connected to the inner end of said shaft, a key-controlled element arranged to be operated from the other side of the casing and provided with
- 15 a lug adapted to engage said first-named lug, whereby the operation of said key-controlled element causes the rotation of said disk, said co-operating lugs normally locking said disk against operation by said
- 20 knob, and spring means for normally holding said first-named lug in position to be engaged by the lug on said element, said lugs being separable by an axial movement of said shaft to permit rotation of said disk
- 25 by the knob.
5. In a lock, a casing having an edge provided with an opening, a locking disk rotatably supported within said casing and having a segment cut away to form an edge
- 30 adapted to lie substantially flush with said edge of the casing when the disk is in normal or unlocking position, a portion of said disk projecting through said opening beyond said edge of the casing when the disk
- 35 is in locking position, a knob projecting from one side of the casing in axial alignment with said disk for turning the same, a key-controlled element arranged in axial alignment with said disk and adapted to be operating
- 40 from the other side of the casing, a lug on said element, a member slidably and non-rotatably connected with said disk at the center thereof, said member being rigidly connected with said knob, a lug on
- 45 said member arranged to be engaged by the lug on said element, whereby the operation of said key-controlled element effects the operation of said disk, said cooperating lugs normally locking said disk against
- 50 movement by said knob, and means for normally holding said lugs in locking position, said member being separable from said element by an axial movement of said knob to permit operation of said disk by the knob.
- 55 6. In a lock, a casing having an edge provided with an opening, a locking disk rotatably supported within said casing and having a segment cut away to form an edge adapted to lie substantially flush with said
- 60 edge of the casing when the disk is in normal or unlocking position, a portion of said disk projecting through said opening beyond said edge of the casing when the disk is in locking position, a knob projecting from
- 65 one side of the casing and having a shaft op-

eratively connected at its inner end with said disk for turning the latter into locking and unlocking positions, said shaft being axially movable without breaking its operative connections with said disk, a projection connected with said shaft, a stop arranged in the path of said projection to lock said disk against operation by the knob, said projection being movable out of the way of said stop by an axial movement of said shaft, 75 whereupon the knob may be turned to rotate said disk, and spring means for normally holding said projection in the path of said stop.

7. In a lock, a casing having a straight edge provided with a flanged slot, a passive locking disk rotatably mounted within said casing, said disk having a peripheral flange extending axially from one side only of the main body, a segment of said disk cut away 80 to form a straight flanged edge at a distance from the center of the disk and adapted to lie in said flanged slot substantially flush with said straight edge of the casing when the disk is in unlocking position, a flanged portion of said disk projecting through said slot beyond said straight edge of the casing when the disk is in locking position, a keeper having a straight edge adapted to lie closely 85 parallel to the straight edge of the casing and having a curved shoulder arranged to interlock with the flange of said disk when the latter is in locking position, a shaft projecting from one side of the casing in axial alignment with said disk and operatively 90 connected thereto, a knob at the outer end of said shaft, and key-controlled means also in axial alignment with said disk for operating the same from the other side of the casing.

95 8. In a lock, a casing having a straight edge provided with a flanged slot, a passive metal disk rotatably mounted within said casing and having a non-circular hole at the center, the metal of said disk being bent laterally at one side of the periphery to form a flange, a segment of said disk being cut away 100 to form a straight flanged edge at a distance from the center of the disk and adapted to lie in said flanged slot substantially flush with said straight edge of the casing when the disk is in unlocking position, a flanged portion of said disk projecting through said slot beyond said straight edge of the casing 105 when the disk is in locking position, a keeper having a straight edge adapted to lie closely parallel to the straight edge of the casing and having a curved shoulder arranged to interlock with the flange of said disk when the latter is in locking position, a member 110 engaging in the center hole of said disk, a knob at one side of the casing in axial alignment with said disk and having a shaft connected to said member, and key-controlled means also in axial alignment with said disk 115

120 9. In a lock, a casing having an edge provided with an opening, a locking disk rotatably supported within said casing and having a segment cut away to form an edge adapted to lie substantially flush with said

125 edge of the casing when the disk is in normal or unlocking position, a portion of said disk projecting through said opening beyond said edge of the casing when the disk is in locking position, a knob projecting from

130 one side of the casing and having a shaft op-

for operating the disk from the other side of the casing.

9. In a lock, a flat and substantially circular casing having a straight edge provided 5 with an opening, said casing forming a shallow and substantially circular chamber, a passive locking disk rotatably mounted within said chamber and practically filling the same, said disk having a segment cut away 10 to provide a straight edge, whereby said disk is wholly within the casing when in unlocking position, a portion of said disk projecting through said opening when the disk is in locking position, a shaft projecting 15 from one side of said casing in axial alignment with said disk and extending at its inner end into operative engagement with said disk, a knob at the outer end of said shaft, key-controlled means for operating said disk 20 from the other side of the casing, and means projecting out of the casing on the same side as said shaft for engaging said disk and thereby locking the same in locking position 25 against operation by said key-controlled means.

10. In a lock, a rotatable locking disk hav-

ing an arcuate slot, a knob for turning said disk into locking and unlocking positions, a fixed stop arranged to engage the ends of 30 said slot to limit the rotary movements of the disk in opposite directions, a movable stop arranged to engage one end of said slot when the disk is in locking position and thereby lock said disk in that position, and means for operating said movable stop. 35

11. In a lock, a casing, a rotatable locking disk within said casing, a portion of said disk being adapted to project out of the casing when the disk is in locking position, a fixed plate, a rotatable element mounted on 40 said plate in axial alignment with said disk, a knob projecting from one side of the casing in axial alignment with said disk for operating the same, a key-actuated member arranged to be operated from the other side of 45 the casing and connected with said element, said cooperating parts normally locking said disk against operation by said knob, and means for rendering said parts inoperative to permit rotation of said disk by said knob. 50

FREDERICK W. ANDREW.
